[57] **CLAIM**

The ornamental design for a single unit battery charger for multiple batteries, as shown and described.

DESCRIPTION

FIG. 1 is a right side, top and back perspective of a single unit battery charger for multiple batteries showing my design, the broken lines showing a battery are included for the purposes of illustrating environmental structure and form no part of the claimed design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.
